(57) **CLAIM**

The ornamental design for a fender for an automotive vehicle, as shown.

DESCRIPTION

FIG. 1 is a front perspective view of the fender for an automotive vehicle;

FIG. 2 is a rear perspective view thereof;

FIG. 3 is a top plan view thereof;

FIG. 4 is a bottom plan view thereof;

FIG. 5 is a left side elevation view thereof;

FIG. 6 is a rear elevation view thereof;

FIG. 7 is a right side elevation view thereof; and,

FIG. 8 is a front elevation view thereof.

The broken lines shown in the drawings illustrate environmental structure for the fender for an automotive vehicle that forms no part of the claimed design.
